UNITED STATES PATENT OFFICE

2,445,839

GOLF SWING INDICATOR

Albert M. Newman and Randall V. Miller,
Los Angeles, Calif.

Application May 13, 1946, Serial No. 669,337

9 Claims. (Cl. 273—35)

1

This invention relates to test, corrective, and teaching equipment, and particularly to such equipment to be used in the playing of golf.

It is well-known in the game of golf that stance is one of the prime factors bearing on the ability of a golf player to play the game well. With minor exceptions, the position and swing of a golf player determines the distance and accuracy of the flight of the ball. One of the indications of the proper stance of a golf player is the position of his head, it being well-known that if the head shifts to too great an extent, either forward or backward, with respect to the direction of flight of the ball, or upwardly, during the stroke, either the club head will not properly contact the ball, or the desired amount of impact will not be given to the ball.

The present invention is directed to a device which will permit freedom of movement of the body, arms, and club, while indicating any undesirable extent of movement or shift of the head both along the line of flight of the ball and in a direction transverse to the direction of flight of the ball. Furthermore, if the movement of the head is at an upward angle, such movement will also be indicated. The device provides permissible movement within limits consistent with a good golf swing, but indicates any movement beyond these permissible limits. In general, the device consists of an electrical contact device which may be attached to the head of the golfer, and which will indicate to the golfer, or to an instructor, any movement and its direction beyond permissible limits.

The principal object of the invention, therefore, is to facilitate the teaching and learning of good golf playing.

Another object of the invention is to provide a device for indicating improper body movements during a golf swing.

A further object of the invention is to provide an indicator of the movement of a golfer's head beyond permissible limits during a golf stroke.

A still further object of the invention is to provide an indicator of a golfer's movements during the course of a golf swing.

Although the novel features which are believed to be characteristic of this invention will be pointed out with particularity in the appended claims, the manner of its organization and the mode of its operation will be better understood by referring to the following description read in conjunction with the accompanying drawings, forming a part hereof, in which:

2 Fig. 1 is a perspective view of the device embodying the invention in operation.

5 Fig. 2 is a cross-sectional view of the indicator of the invention taken along the line 2—2 of Fig. 1, and

Fig. 3 is a schematic diagram of the electrical circuit of the invention.

Referring now to the drawings, in which the same numbers identify like elements, a box or 10 casing 5 with a cover 6 houses the mechanism for indicating movements of a golfer's head as indicated. A band 7 is placed around the golfer's head and through a cord 8 is connected with an armature element 10 protruding from an opening 15 11 in the sloping panel 12 of the casing 5. At 15, 16, and 17, are indicator lights, while an opening may be provided at 20 for permitting sound to pass freely from the interior of the casing to the outside.

20 Referring now to Figs. 2 and 3, on the left side of the opening 11 is a metallic electrode 21; on the right side, a metallic electrode 22; and on the upper side, a metallic electrode 23. The armature 10 is metallic, and may be pivoted or 25 otherwise attached to the back of the casing 5. As shown in the drawing, one end of a spring 25 is wrapped around a mounting post 26 and the end of armature 10. This type of mounting permits the armature 10 to be rigid. Should a 30 flexible armature be used, its end could be fixedly attached to the back of the case. The lamps 15, 16, and 17 may have differently colored globes, such as red, white, and green, while, in shunt thereto, are buzzers 27, 28, and 29 which are each 35 tuned to generate a different tone. It is realized, of course, that only two lights 15 and 16 may be used with a buzzer 29 or other different combinations, although to provide both aural and visual indications in all three directions, the 40 triple indicators, as illustrated, are preferred.

45 Any suitable source of energy, such as a dry cell 31, is provided, together with a master switch 32, which may be arranged to be closed when the cover 6 is opened. The armature 10 is mounted so that in its rest position it is equidistant from electrodes 21, 22, and 23. However, electrode 23 may be adjusted closer to the armature 10 than electrodes 21 and 22, if desired, to indicate a less upward movement than horizontal movement of the head. With the switch 32 closed, it 50 is realized that if the armature 10 makes contact with either of the electrodes 21, 22, or 23, a circuit will be made and the respective lamps 15, 16, and 17 with buzzers 27, 28, and 29 will be energized. If the armature 10 is moved to 55

the right-hand corner of the aperture 11, then both electrodes 22 and 23 may be contacted and the respective lamps 16 and 17, and buzzers 28 and 29 will be energized. If the movement is to the upper left-hand corner of the aperture 11, then lamps 15 and 17 and buzzers 27 and 29 will be energized.

Although the amount of movement of the band 7 is determined by the distance between the armature 10 and the contacting electrodes 21, 22, and 23, it is realized that the length of the cord 8 will determine the permissible movement of the head of the golfer before contact is made. Thus, the permissible limits may be determined either by the adjustment of the electrodes with respect to the armature, the pivot point of the armature, or the length of the cord 8, the latter being accomplished by the adjusting buckle 34 at the end of the cord. This buckle also permits the proper length to be provided for golfers varying in height.

In operation, the indicator is set on the ground in front of the golfer, the band 7 placed on his head, the length of the cord 8 adjusted, and the ball 33 placed at the proper position in front of the golfer. The golfer then makes his swing, and, if light 15 and buzzer 27 are energized, it is evident that the golfer's head has moved too far to his left during his swing. Likewise, if his head moves too far to the right, the light 16 and buzzer 28 will be energized, while, if he raises his head beyond the proper limit, then the lamp 17 and buzzer 29 will so indicate. As mentioned above, if he moves his head too far forward and also too high, then both lamps 15 and 17 and buzzers 27 and 29 will so indicate, while too great a movement to the right and also upwardly will be indicated by buzzers 28 and 29 and also lamps 16 and 17.

The above-described device has been found, in operation, to be very satisfactory, not only in teaching the golfer the proper golf swing, but also to test or determine whether a golfer is going beyond permissible limits during his swing. It is particularly effective, since it does not interfere with the swing, part of the cord being elastic so excessive head movements are not prevented but only indicated.

We claim:

1. A device for indicating bodily movement exceeding predetermined limits comprising a casing having a square sided aperture therein, a plurality of electrodes within said aperture, said electrodes being positioned on a plurality of the sides of said aperture, an armature extending between said electrodes, a separate electric circuit for each of said electrodes, each of said circuits including said armature, and indicating means in each of said circuits to indicate contact between said armature and a respective electrode.

2. A device in accordance with claim 1, in which means are connected to said armature and extending to a remote point, movement beyond predetermined limits at said remote point causing said armature to contact at least one of said electrodes.

3. A device in accordance with claim 1, in

which said indicating means includes a plurality of lamps and sound producing means.

4. A device for indicating direction of movement of a person beyond predetermined limits comprising a casing having an observable panel, a four-sided aperture in said panel, an armature extending through said aperture substantially at the center thereof, a contact element on at least three sides of said aperture, a plurality of lamps on said panel, a plurality of circuits, each circuit including a lamp and an electrode and said armature, and means attached between said person and said armature.

5. A device in accordance with claim 4, in which one electrode and lamp circuit indicates movement of said person to the left, another electrode and lamp circuit indicates movement of said person to the right, and a third electrode and lamp circuit indicates an upward movement of said person.

6. A device for producing indications when predetermined limits of movements of a person are exceeded during a golf swing comprising a box adapted to be positioned in front of said person, an aperture in said box facing said person, an armature extending through said aperture, means connected to said armature and said person, movement of said person beyond predetermined limits causing said armature to contact at least one side of said aperture, and means in said box to indicate contact between said armature and the sides of said aperture.

7. A device in accordance with claim 6, in which said last mentioned means includes electrodes at the sides of said aperture, an electrical energy supply, electrical aural indicators and separate circuits for each of said electrodes and indicators, said circuits including said armature.

8. A device for producing indications when predetermined limits of movement of a person are exceeded during a golf swing comprising a box adapted to be placed in front of said person, a movable element in said box, a cord connecting the head of said person and said movable element, and means in said box to indicate when the head of said person has moved beyond said permissible limits.

9. A device in accordance with claim 8, in which said last mentioned means includes differentiated visible indicators for different directions of movement of the head of said person.
